UNITED STATES PATENT OFFICE.

CLARENCE W. HUNT, OF FORT WAYNE, INDIANA.

DISH-WASHING MACHINE.

1,259,743.

Specification of Letters Patent. Patented Mar. 19, 1918.

Application filed July 25, 1916. Serial No. 111,228.

To all whom it may concern:
Be it known that I, CLARENCE W. HUNT, a citizen of the United States, residing at Fort Wayne, in the county of Allen, State of Indiana, have invented certain new and useful Improvements in Dish-Washing Machines; and, I do hereby declare the following to be a full, clear, and exact description of the invention, such as will enable others skilled in the art to which it appertains to make and use the same.

This invention relates to a dish-washing machine.

An object of the invention resides in the provision of a novel construction in a machine of this character whereby the dishes will be washed by the forcible splashing of water thereon in various directions.

A further object of the invention resides in so constructing the machine that the change of direction in which the water is thrown will be automatic.

A still further object of the invention resides in the general improvement of the construction of machines of this character.

With these and other objects in view, such as will appear as my description progresses, my invention comprises the combination and arrangement of parts as set forth in and falling within the scope of the appended claims.

In the drawing:

Figure 1 is an end elevation of a machine constructed in accordance with my invention;

Fig. 2 is a similar view looking at the opposite end;

Fig. 3 is a transverse sectional view;

Fig. 4 is a longitudinal sectional view;

Fig. 5 is a detail showing the manner in which the dish carrying tray is mounted, and

Fig. 6 is a fragmental section of one end of the machine.

The embodiment of the invention illustrated in the drawing includes a base 1 on one end of which a support is mounted which is provided with upwardly extending spaced arms 2 and 3. Rotatably mounted in the upper end of the arm 2 is a casting 4 on one end of which a gear 5 is formed and on the other end of which a socket 6 is formed. One end of a cylindrical casing 7 is secured to this casting and the socket 6 is located within the casting. The other end of the casing is provided with a hinged cover 8 on

which a bearing member 9 is mounted. A dish supporting tray is mounted within the casing 7 and is semi-cylindrical in form, being formed of screen cloth. This tray is provided with a solid bottom 10 on which a plurality of upwardly projecting lugs 11 are formed. One end of this tray is provided with a trunnion 12 which extends into the socket 6 so that the socket may rotate on the trunnion. The other end of the tray is provided with a trunnion 13 which is supported, when the cover 8 is open, by a hook 14 on the end of a chain 15, which latter is secured to the casing 7. This trunnion 13 extends through the bearing member 9 on the cover 8 and is provided with a squared end for the reception of the upper end of a support 16, which latter is U-shaped in form and is hinged, at 17, to the base 1. This support serves to support the casing 7 when the latter is in its operative position. This casing is, however, supported when the support 16 is disengaged from the trunnion 13 by a bracket 18. At the opposite end of this casing 7 is a drain cock 19 and located intermediate the ends is a water inlet port 20 which is provided with a suitable cover. The dish supporting tray is provided with a plurality of transversely extending rods 21 which project between the upper edges thereof and between which the plates are supported. A plurality of U-shaped supporting members 22 extend upwardly from the upper edges of the tray and are provided with hooks 23 for the reception of cups. The inner side of the casing 7 has a plurality of fins 24 which extend longitudinally thereof and which, when the casing revolves, agitate the water therein.

In order that this casing may be revolved I have mounted a shaft 25 in bearings in the arms 2 and 3 of the standard, which shaft is provided with a crank handle 26. Secured to this shaft 25 is an interrupted gear 27 which meshes with the gear 5 aforementioned. Extending radially from the shaft 25 is a pair of arms 28 which support a segmental internally toothed rack 29, the teeth of which mesh with the gear 5. With this arrangement when the crank handle 26 is operated the gear 5 will be rotated in one direction by virtue of the engagement of the interrupted gear 27 therewith. As soon as this gear 27 is disengaged from the gear 5 the teeth on the rack 29 will engage with the gear 5 and the continued movement of

the crank handle 26 will cause the rack 29 to rotate the gear 5 in a reverse direction. Inasmuch as the casing 7 is rigidly associated with the casting on which the gear 5 is formed the casing will be moved alternately in opposite directions and the water within the same will therefore be agitated and thrown forcibly against the dishes. The mounting of the dish carrying tray is such 10 that it will remain stationary during the revolution of the casing 7.

It will be obvious that when the support 16 is disengaged from the trunion 13 the casing 7 will be supported on the bracket 15 18 and that at this time the chain 15 will support the dish receiving tray.

While I have illustrated and described a particular embodiment of my invention, it has merely been for the sake of convenience 20 and I do not wish to be limited to that particular embodiment as it is obvious that numerous changes may be made in the details of construction without departing from the spirit of the invention or exceeding the 25 scope of the appended claims.

What I claim is:—

1. In a dish washing machine, a casing having a permanent closed end and an op-

posite hinged end, a tray centrally arranged in the casing and having one end journaled in said closed end and its opposite end journaled in said hinged end of the casing, and a flexible hanger connected with the casing and the tray to support the latter when the hinged end of the casing is open. 30 35

2. In a dish washing machine, a casing having a permanent closed end and an opposite hinged end, a tray centrally arranged in the casing and having one end journaled in said closed end and its opposite end journaled in said hinged end of the casing, a flexible hanger connected with the casing and the tray to support the latter when the hinged end of the casing is open, and supports for the casing and tray, one of the 40 45 supports being swingingly mounted at the hinged end of the casing to be moved outwardly therefrom to permit the opening of the hinged end.

In testimony whereof, I affix my signature, 50 in the presence of two witnesses,

CLARENCE W. HUNT.
